CLAIM

The ornamental design for a line straightening hand tool, as shown and described.

DESCRIPTION

FIG. 1 is a perspective view of our line straightening hand tool, showing the new design;

FIG. 2 is right-side elevation view of the line straightening hand tool in FIG. 1;

FIG. 3 is a left-side elevation view of the line straightening hand tool in FIG. 1;

FIG. 4 is a front elevation view of the line straightening hand tool in FIG. 1;

FIG. 5 is a rear elevation view of the line straightening hand tool in FIG. 1;

FIG. 6 is a top plan view of the line straightening hand tool in FIG. 1;

FIG. 7 is a bottom plan view of the line straightening hand tool in FIG. 1; and,

FIG. 8 is an exploded perspective view showing the line straightening hand tool, with a line shown in broken lines.

The broken lines portions in the drawings illustrate environment and form no part of the claimed design.
